UNITED STATES PATENT OFFICE

HOWARD M. WYLIE AND HAROLD E. ADAMS, OF SOUTH NORWALK, CONNECTICUT,
ASSIGNORS TO NASH ENGINEERING COMPANY, OF SOUTH NORWALK, CONNECTICUT, A CORPORATION OF CONNECTICUT

VACUUM STEAM HEATING SYSTEM

Application filed January 4, 1928. Serial No. 244,513.

This invention relates to heating systems of the low pressure or vacuum type in which pumps are provided for removing air from the system and for returning the water of condensation to the boiler.

It is one object of our invention to provide improved connections in such a system, by which the return flow of the condensate is materially assisted.

10 A further object is to provide a construction by which the return flow of the condensate to the boiler may be automatically accomplished in case of disability of the pumping apparatus.

15 Our invention further relates to arrangements and combinations of parts which will be hereinafter described and more particularly pointed out in the appended claims.

A preferred form of our invention is shown 20 in the drawings in which—

Fig. 1 is a diagrammatic perspective view of portions of a vacuum steam heating system, and

25 Fig. 2 is a perspective view of a slight modification.

Referring to Fig. 1, we have shown a low pressure or vacuum steam heating system comprising a boiler 10, a supply pipe 11, a radiator or other heat radiating apparatus 30 12, and a return pipe 13. The radiator 12 is connected by an inlet pipe 14 to the supply pipe 11 and is connected through a steam trap 15 and discharge pipe 16 to the return pipe 13. It will be understood that the heating system commonly comprises a large number of radiators 12 or other radiating apparatus, all of which, however, are connected between the supply pipe 11 and return pipe 13 substantially as indicated.

40 The condensate from the radiators flows down through the return pipe 13 to a separating tank 20, to which suitable pumping apparatus 21 is connected. The pumping apparatus preferably comprises an air pump for withdrawing air from the tank 20 and discharging the same through a separator 22 to a vent pipe 23, and a centrifugal water pump adapted to withdraw the water or condensate from the tank 20 and to deliver the 45 same through a discharge pipe 25 to the boiler 50

10. The apparatus thus far described is of the usual commercial type and in itself forms no part of our present invention.

An undesirable condition sometimes arises in vacuum or low pressure heating systems 55 of the type above described, if the fires are too tightly banked under the boiler or if the system is for any other reason permitted to cool down to too great an extent. Under these conditions, a vacuum may be formed on the 60 supply side of the system, sufficient to prevent flow of condensate from the radiators 12 through the return pipe 13 to the tank 20.

To offset this condition, it has been proposed to provide a by-pass or equalizing connection, as the pipe 30, between the supply pipe 11 and some point on the return side of the system, such as the top of the tank 20. A check valve 31 in the pipe 30 opens toward the supply pipe 11 and prevents the flow of 70 vapor or steam in the opposite direction toward the return pipe 13, whenever the pressure in the supply pipe 11 exceeds the pressure in the return pipe 13, which is the normal operating condition.

75 One feature of our invention consists in providing a branch connection 32 from an intermediate point in the equalizing pipe 30 to an elevated point in the return pipe 13, and in providing a check valve 33 in the pipe 30 between the tank 20 and the branch pipe 32, said check valve opening away from the tank 20.

80 The object of the branch connection 32 is to permit the flow of air or vapor from the tank 20 to an elevated point in the return pipe 13 at the same time that the water of condensation flows down in the pipe 13 to the tank 20. This avoids the necessity of 85 the air finding its way upward through the same pipe in which the water is descending, and greatly improves the circulation in the lower part of the pipe 13, accomplishing a more rapid and uniform flow of the condensate to the separating tank 20.

90 We have also provided a by-pass connection 40 from the lower end of the return pipe 13 to the discharge-pipe 25 beyond the pumping apparatus 21. A check valve 41 is 100

provided in the pipe 40, opening toward the boiler 10.

The vent pipe 23 in the usual practice is merely a short discharge pipe for the separator 22 but a feature of our invention is the extension of the vent pipe 23 upward far enough to care for a head greater than the pressure to be overcome in returning the condensate to the boiler.

10 In the operation of such heating apparatus, the pumping mechanism occasionally fails by reason of an interruption in the supply of electric power or for some other reason, but it is essential that the return of condensate to the boiler shall continue without substantial interruption. By the use of the connections above described, a head of water may be built up in the return pipe 13 sufficient to overcome the difference in pressure between 15 the return pipe and the boiler and to return the condensate to the boiler, by-passing the same around the stalled pumping apparatus.

As previously stated, the vent pipe 23 extends to a height corresponding to a head 25 greater than is necessary for returning the condensate, so that no water will leave the system by overflow from the vent pipe while building up a pressure in the return pipe in excess of the boiler pressure.

30 In some cases it may not be desirable to extend the vent pipe to so great a height, and in such cases we may substitute the construction shown in Fig. 2, in which the vent pipe 23 is connected to a chamber 44 having an 35 open discharge pipe 45 and a valve 46 controlled by a float 47. Under normal conditions, the chamber 44 contains little water, the valve 46 is open, and the entire structure acts as an ordinary vent pipe. If, however, 40 the head of water built up in the return pipe causes water to rise through the vent pipe 23 to the chamber 44, the float 47 will close the valve 46 and prevent over-flow of water through the discharge pipe 45.

45 From this description, it will be seen that we have facilitated the return of the water of condensation to the separating tank 20 and that we have provided for automatically bypassing the condensate around the pumping 50 apparatus, if disabled, both of these matters being of great importance in the operation of a vacuum heating system.

Having thus described our invention and the advantages thereof, we do not wish to be limited to the details herein disclosed otherwise than as set forth in the claims, but what we do claim is:—

1. In a vacuum steam heating system, a boiler, a circulation system including a supply pipe, radiating apparatus, a return pipe, pumping apparatus effective to remove air from the system and to return the water of condensation to the boiler, and an additional connection from said pumping apparatus to 60 an elevated point in said return pipe, permit-

ting up-flow of air and vapor therethrough as the water of condensation flows downward in said return pipe to said pumping apparatus.

2. In a vacuum steam heating system, a boiler, a circulation system including a supply pipe, radiating apparatus, a return pipe, pumping apparatus effective to remove air from the system and to return the water of condensation to the boiler, an equalizing connection between the supply and return sides 70 of the system permitting flow of air and vapor toward said supply pipe in the event of abnormally low pressure in said supply pipe, means to prevent reverse flow in said equalizing connection, and a branch connection from said 75 equalizing connection to an elevated point in said return pipe, permitting up-flow of air and vapor therethrough as the water of condensation flows downward in said return pipe to said pumping apparatus.

3. In a vacuum steam heating system, a boiler, a circulation system including a supply pipe, radiating apparatus, a return pipe, pumping apparatus effective to remove air from the system and to return the water of 80 condensation to the boiler, an equalizing connection between the supply and return sides of the system permitting flow of air and vapor toward said supply pipe in the event of abnormally low pressure in said supply pipe, a 85 branch connection from said equalizing connection to an elevated point in said return pipe, permitting up-flow of air and vapor therethrough as the water of condensation flows downward in said return pipe to said pumping apparatus, and means to prevent reverse flow through said branch connection and through said equalizing connection.

In testimony whereof we have hereunto affixed our signatures.

HOWARD M. WYLIE.
